(57) **CLAIM**

The ornamental design for a housing for electricity distribution boards, as shown and described.

DESCRIPTION

The patent or application file contains at least one drawing executed in color. Copies of this patent or patent application publication with color drawing(s) will be provided by the Office upon request and payment of the necessary fee.

1. Housing for electricity distribution boards

1.1 : Perspective

1.2 : Front

1.3 : Right

1.4 : Left

1.5 : Top

1.6 : Enlarged

The portion of the design shown in the color yellow, in figures 1.1, 1.2, 1.5 and 1.6, which extends to a respective boundary but does not include the boundary, is for the purpose of illustrating portions of the housing and forms no part of the claimed design.

1 Claim, 6 Drawing Sheets
